US00D753480S

(12) **United States Design Patent** (10) **Patent No.:** **US D753,480 S**
Paton et al. (45) **Date of Patent:** **** Apr. 12, 2016**

(54) **CAPSULE**

(71) Applicant: **Conopco, Inc.**, Englewood Cliffs, NJ (US)

(72) Inventors: **Michael Paton**, Royston (GB); **Daniel Thomas Toon**, Epping (GB)

(73) Assignee: **Conopco, Inc.**, Englewood Cliffs, NJ (US)

(**) Term: **15 Years**

(21) Appl. No.: **29/527,391**

(22) Filed: **May 19, 2015**

Related U.S. Application Data

(62) Division of application No. 29/466,849, filed on Sep. 12, 2013, now Pat. No. Des. 732,386.

(30) **Foreign Application Priority Data**

Mar. 21, 2013 (EM) 002206326-0001
Mar. 21, 2013 (EM) 002206326-0002
